UNITED STATES PATENT OFFICE

166,863

COVER FOR A VEHICLE WHEEL

Charles A. McLeod, Birmingham, Mich., assignor
to A. S. Campbell Company, Boston, Mass., a
corporation of Massachusetts

Application September 13, 1951, Serial No. 16,623

Term of patent 14 years

(Cl. D14—30)

To all whom it may concern:

Be it known that I, Charles A. McLeod, a citizen of the United States, residing at Birmingham, county of Oakland, and State of Michigan, have invented a new, original, and ornamental Design for a Cover for a Vehicle Wheel, of which the following is a specification, reference being had to the accompanying drawing, forming a part thereof.

In the drawing:

Fig. 1 is a side elevational view of a cover for a vehicle wheel showing my new design.

Fig. 2 is a front elevational view of same.

Fig. 3 is a vertical diametric section; and

Fig. 4 is a section on line 4—4 of Fig. 1.

The dotted line shown in Figs. 2 and 3 of the drawing is for illustrative purposes only.

I claim:

The ornamental design for a cover for a vehicle wheel, as shown and described.

CHARLES A. McLEOD.
